Charles E. Allen,
Attorney

UNITED STATES PATENT OFFICE.

FRANK W. GOVE, OF ESSEX JUNCTION, VERMONT.

AUTOMATIC REGULATOR FOR STEAM-PIPES.

No. 874,959.

Specification of Letters Patent.

Patented Dec. 31, 1907.

Application filed July 15, 1905. Serial No. 268,814.

To all whom it may concern:

Be it known that I, FRANK W. GOVE, a citizen of the United States, residing at Essex Junction, in the county of Chittenden and State of Vermont, have invented certain new and useful Improvements in Automatic Regulators for Steam-Pipes; and I do hereby declare the following to be a full, clear, and exact description of the invention, such as will enable others skilled in the art to which it appertains to make and use the same.

My invention relates to improvements in automatic regulators for steam supply pipes, leading from the boiler.

The object of my invention is to provide a regulator of this character which is placed upon the steam supply pipe leading from the boiler intermediate the throttle valve and the steam gage, and in which the same is adapted to automatically cut off the supply of steam through said pipe when the steam is at too high a pressure, and adapted to automatically open the supply pipe when the steam pressure has lowered to its normal pressure.

Another object of my invention is to provide means whereby the regulator may be set or adjusted to cut off the steam at any desired pressure, the operation of reopening the valve upon the lowering of the steam pressure being the same.

In the accompanying drawings, Figure 1, is a perspective view of my improved regulator attached to a steam supply pipe. Fig. 2, is a vertical sectional view of the regulator showing the steam supply pipe partly in section.

Referring now to the drawings, 1 represents a portion of the main steam supply pipe which is at a point intermediate the throttle valve, and the steam gage, and said pipe 1 has a branch pipe 2 which has its outer end curved upwardly and adapted to support a cup-shaped member 3 into which is screwed the lower end of the vertically disposed pressure cylinder 4. The said cylinder 4 as shown, is of an elongated form, and vertically disposed in a position parallel with the main steam supply pipe 1, and is provided adjacent its upper end with a sleeve 5 which entirely surrounds the cylinder and secured thereto in any desired manner, and said sleeve is provided with an inwardly extending arm 6 which is connected to a sleeve 7 carried by the main sup-

ply pipe 1, and thus the cylinder is rigidly held by the pipe in a vertical parallel position. The upper end of said cylinder is provided with a piston head 8 which is 60 screwed within the cylinder, and thus is vertically adjustable for the purpose hereinafter more fully described. The said piston head is provided with an opening 9 through which the piston rod passes, and is 65 adapted to freely reciprocate therethrough. The said piston rod extends within the cylinder adjacent the lower end and is provided with a piston 11 which is provided with circumferential grooves therein to receive the metallic packing 12 which forms a tight joint or connection with the inner face of the cylinder. Within the cylinder above the piston and surrounding the piston rod 10, is a coil spring 13 which has its upper 70 end bearing against the cylinder, and its lower end bearing against the piston 12, thus normally holding the piston within the lower end of the cylinder. The tension of said spring upon the piston is increased or 75 decreased by screwing the cylinder head up or down, thus requiring a greater steam pressure in the lower end of the cylinder to move the piston upwardly.

The main steam supply pipe 1 adjacent 85 the upper end of the cylinder is provided with a turning plug 14 by means of which the steam within the supply pipe is cut off, and said plug is provided with an outwardly extending stem 15 which is adapted to pass 90 through an opening in the operating lever 16, said lever provided with a set screw 17 by means of which the operating lever 16 is secured to the valve stem 15 in its adjusted position. The lever 16 is bent laterally at 95 18 to bring the outer bifurcated end 19 in a line with the upper end of the piston rod 10. The said piston rod is provided at its upper end with a rigid arm 20 which extends inwardly and is provided with the outwardly 100 extending pin 21 which passes within the bifurcated outer end 19 of the arm 16, and thus as the piston is moved up and down by the steam and spring, the turning plug 14 is oscillated and the steam passing through 105 the pipe is controlled.

The steam from the supply pipe 1 passes through the branch pipe 2 to the lower end of the cylinder. The set screw 17 is loosened so that the arm 16 is free to move without 110 operating the turning plug 14, and thus the piston within the cylinder is forced upward

by the pressure of the steam until the desired pressure is obtained, which does not as before stated, move the turning plug. When the desired pressure is obtained, the set 5 screw 17 is tightened, thereby locking the arm 16 to the turning plug 14, and any increased pressure within the cylinder moves the piston upward and operates the turning plug 14, and cuts off the steam. The falling 10 of the pressure within the pipe or cylinder will cause the spring 13 to move the piston downward, and thus move the turning plug 14, and allow more steam to pass through the pipe 1, and thus it is readily seen that 15 my device may be set at any desired pressure.

Having thus described my invention, what I claim and desire to secure by Letters Patent, is:—

A device of the character described, comprising a line of supply pipe vertically arranged, a branch pipe connected thereto; a cap-shaped member connected to said branch pipe, a cylinder screwed within the upper end of the cap and in communication therewith, a turning plug in the pipe line above the cylinder, a piston within the cylinder, a cylinder-head carried by the upper end of the cylinder and vertically adjust-

able, a piston rod carried by the piston and extending through the cylinder-head, a coil-spring surrounding the piston rod intermediate the cylinder-head and piston and normally exerting a downward pressure upon the piston, a bracket carried by the pipe line and surrounding the upper end of the cylinder and supporting the same, a sleeve surrounding the upper end of the piston-rod and rigidly secured thereto, an arm formed integral with the sleeve and extending inwardly towards the pipe line, a laterally-extending horizontally-arranged pin carried by the outer end of the arm, and a lever adjustably carried by the stem of the turning plug and extending inwardly and having a bent portion intermediate its ends to bring the outer end in a line with the arm carried by the piston, and the extreme outer end of the lever bifurcated and adapted to receive and retain the pin therein during the reciprocation of the piston-rod.

In testimony whereof I do affix my signature, in presence of two witnesses.

FRANK W. GOVE.
